US00D659707S

(12) **United States Design Patent**
David et al.

(10) **Patent No.:** US D659,707 S
(45) **Date of Patent:** ** May 15, 2012

(54) **DISPLAY SCREEN WITH GRAPHICAL USER INTERFACE**

(75) Inventors: **Darren David**, San Francisco, CA (US); **Joshua Santangelo**, Seattle, WA (US); **Luis Eduardo Cabrerra-Cordon**, Bothell, WA (US); **John E. Inman**, Duvall, WA (US)

(73) Assignee: **Microsoft Corporation**, Redmond, WA (US)

(**) Term: **14 Years**

(21) Appl. No.: **29/382,505**

(22) Filed: **Jan. 4, 2011**

(51) **LOC (9) Cl.** 32-00

(52) **U.S. Cl.** **D14/487**; D14/493

(58) **Field of Classification Search** D14/485-495; 715/700-867, 973-977

See application file for complete search history.

(57) **CLAIM**

The ornamental design for a display screen with graphical user interface, as shown and described.

DESCRIPTION

The FIGURE is a front view of a display screen with graphical user interface showing the new design.

The broken line showings of the display screen and the images within the square regions are for environmental purposes only and form no part of the claimed design.

1 Claim, 1 Drawing Sheet
